Claims priority, application Italy May 18, 1960
4 Claims. (Cl. 101—181)

The present invention has for its subject a system for regulating the longitudinal positional setting or registration on machines used for performing repetitive operations on a continuous band, such as, for example machines used for printing by superimposing monochromatic images (of the rotogravure or similar type). The regulation of the longitudinal registration consists in this case in adjusting the position of the individual monochromatic images so as to obtain a very high degree of precision of superimposition between the several images—which must normally be correct to the tenth of a millimetre.

In the present art, the relative positions of two monochromatic images from two printing rollers are checked by measuring the time lapse between the reading of a reference mark forming part of one image printed by one roller, and the reading of a control mark forming part of the image printed by a subsequent roller or engraved directly thereon: if said second mark is printed on the paper, then the check is of the paper-to-paper type, and if it is engraved on the roller, the check is of the paper-to-roller type.

In the present state of the art, said time lapse is measured and a system of any kind is used to determine the speed of the machine at the instant of measurement; given the time lapse and the machine speed, the space corresponding to the error can be deduced therefrom; this may be termed the analogue type of measurement inasmuch as it has all the characteristics of systems known by this name in the art of electronic computers.

An object of the present invention is to provide a system which can be defined as digital: this system, which comprises an impulse counter, is based on the counting of the number of impulses emitted in the interval of time which elapses between the two respective readings of a reference mark and a control mark, by means of two reading heads; a system is then provided which is designed to correct the error in accordance with the number of impulses counted.

Two embodiments of the present invention will now be described with reference to the accompanying drawing wherein:

FIG. 1 shows schematically an example of a machine for printing on a continuous band by means of rollers;

FIG. 2 shows schematically an example of the device according to the present invention;

FIG. 3 shows schematically a second example of a device according to the invention;

FIG. 4 shows schematically a detail relating to the device in said FIG. 3;

FIG. 1 shows a diagram of the printing machine where in the various component parts of the machine are visible.

The band of paper to be printed, indicated by the numeral 2, unwinds from the reel indicated by the numeral 1, passes through a set of transporter members and is brought into contact with the printing rollers indicated by the symbols C₁ to C₅.

Said rollers C₁ to C₅ are caused to rotate by means of a main motor 3 on whose shaft 4 are keyed the gears indicated by the symbols A₁ to A₅; these are respectively in mesh with the gears indicated by the symbols B₁ to B₅.

2

The first roller C₁ is driven directly from shaft 4; for each of the remaining rollers from C₂ to C₅ there is provided a differential unit coupled to a correcting motor, thereby permitting the rollers to rotate independently from the others in order to correct their respective positions. Said differential units are indicated by the symbols S₂ to S₅ and the related correcting motors by the symbols M₂ to M₅.

Errors occurring in the superimposition of the images can be corrected not only by means of said correcting action on the rollers, but also by varying the length of the section of paper band 2 between the two rollers which respectively print the two images with said error of superimposition. To this end, some of the transporting members relating to the sections of band between the rollers, 15 are made movable.

In the same FIG. 1 the reading heads L₂ to L₅ directed to the band of paper, and the reading heads N₂ to N₅ adapted to read from the rollers themselves, are also indicated.

With the paper-to-paper type of check, that is where there are two reading heads checking the relative positions of two marks printed on the paper respectively by one roller and by a subsequent roller C₂ to C₅ in respect of which the check is being performed, the two reading heads corresponding to said roller C₂ to C₅ to be checked are both incorporated in the device L₂ to L₅; this device, as can be seen from said FIG. 1, is in fact placed after the related roller C₂ to C₅.

With the paper-to-roller type of check, that is where 30 two reference marks are read, one printed on the paper by a roller and the other engraved on a subsequent roller C₂ to C₅ to be checked, one reading head (not shown in the drawing for the sake of simplicity) is provided before said roller C₂ to C₅ and another reading head N₂ to N₅ is also provided for the purpose of reading said mark engraved on roller C₂ to C₅.

Lastly in FIG. 1 there is shown an impulse or signal generator 5 which can be a transparent disc on which radial marks have been traced. The marks are sensed 40 or read by a photoelectric system while they are being rotated by the main shaft 4. A device of this kind is sold by Wel Gurley of Troy, New York, under Model 8603.

A magnetic device similar to the photoelectric system can also be used.

FIG. 2 shows a diagram of a device for correcting the error occurring in the superimposition of two images one on the other.

In FIG. 2 there can be seen the impulse generator 5 which is directly connected to the driving shaft 4; the numeral 15 is a schematic representation of the mechanical connecting member between said shaft and said generator; in this example the frequency of the impulses depends on the speed of the machine.

Since for a given angular movement of the driving shaft 55 4 there is a corresponding given linear movement of the band, that is, for every revolution of the shaft a constant length of band is advanced, and since generator 5 is connected directly to shaft 4, it follows that impulse generator 5 generates a constant number of impulses for unit length 60 of paper, irrespective of the speed of advancement of the paper itself.

In the present example, two reading heads 6 and 7 are provided which are each capable of supplying an impulse whenever a mark (reference or control) passes thereunder. One of the two heads, head 6 for example, serves as a reference head, while the other, 7 serves as a control head. In this example head 6 is deemed to be the one which reads the position of the reference mark of the image printed on the paper band 2 before the roller in 70 respect whereto the check is to be performed, while head 7 is deemed to be the one which reads the position of the control mark which can be on the roller itself with re-

spect whereto the check is to be performed: we have thus the paper-to-roller type of check, the error being read before the roller being checked prints its monochromatic image. Said check mark may also, as mentioned hereinabove, be read on the monochromatic image printed on band 2 of said paper by the roller to be checked, and in this case we have the paper-to-paper type of check, the error being read after printing by the roller being checked.

In both of the cases hereinabove referred to, that is paper-to-roller and paper-to-paper checking, the positions of the two heads are such that, when the error is nil, which means that the two images are perfectly superimposed, the two signals are emitted simultaneously by their respective heads. If the impulse coming from head 7 is ahead of the impulse coming from head 6, then there is an error of advancement, that is the roller being controlled is so mis-timed that it prints the image in a position which is in advance of, on the paper, the image previously printed by the other roller (the reference roller); similarly, if the impulse coming from head 7 is behind that coming from head 6, then the error will be one of retardation.

Each of the two reading heads 6 and 7 is connected to the starting circuit 8 shown on page 57 of the "Handbook of Electronic Control Circuits," McGraw-Hill Company, New York, 1959, of high-speed electronic counter 10 such as that shown on pages 60 and 61 of the "Handbook of Electronic Control Circuits," McGraw-Hill Company, New York, 1959, so that the first impulse which arrives from a head (6 or 7) switches in said starting circuit 8, while the second impulse cuts it out.

During the time when starting or gate circuit 8 is in operation, that is in the interval between the two impulses, counter 10 counts the impulses generated by the impulse generator 5.

It should be noted that the impulse generator continually generates impulses for the sole reason that shaft 4 of the machine is in motion, whether such impulses are counted or not. However, the impulses emitted by the generator are counted during said interval, and the content of the counter at the end of the counting process, that is after the emission of the second impulse by the heads, determines the amount of the error.

Said counter 10 is also connected to two error correcting devices respectively for advancement (11) and retardation (12). The two heads 6 and 7 are also connected to a sign detector 9 which is in turn connected to said devices 11 and 12.

It follows that, when counter 10 has finished counting the number of impulses corresponding to a given error, the counter itself causes one or other of the two devices 11 and 12 to come into action; to be precise, the device which is selected by the sign detector 9 will come into action according as to whether said sign detector receives the signal first from head 6 or from head 7.

If, for example, head 7 is the first to emit a signal, then there is an error of advancement, that is, the roller being rotated too fast.

In this case, since the impulse emitted by head 7 precedes that emitted by head 6, sign detector 9 will select correction device 12, which means that said device will come into action after the emission of the impulse from head 6, that is when counter 10 has finished counting.

If on the other hand, head 6 emits its impulse first, the advancement correction device 11 will come into action at the end of the count. A control device 13 similar to impulse generator 5 is also provided for the purpose of acting on counter 10 in order to stop the correction device when the correction has reached a value equal to the value of the error or dependent thereon; said device 13 is mechanically connected to devices 11 and 12 through a connection represented by 14 and is actuated thereby; the same device 13 is also electrically connected to counter 10.

Since the correction involves a movement which is measurable in units of length, it is possible to generate an impulse, by means of device 13, for each unit length of correction.

Besides this it follows from what has been stated that said counter also counts an impulse for each unit of error, said impulse being emitted by generator 5; thus, by imposing the condition that the length corresponding to each error impulse (emitted by generator 5) be equal to the length corresponding to each correction impulse (emitted by device 13), it will happen that if the counter has counted n impulses, corresponding to a given error ϵ , when device 13 has emitted n impulses, a correction will have been made which is also equal to ϵ . Device 13, through the n impulses emitted, will have zeroized the contents of counter 10 and hence the latter will cease to correct, that is it will halt device 11 or 12 which has carried out the correction.

In practice it may be useful to cause the correction to stop before the contents of the counter are at zero, that is when device 13 has emitted a number r of impulses fewer than said number n , which means that it can be arranged for counter 10 to cause the correcting device (11 or 12) to stop when the contents of the counter are equal to $n-r$.

In this case, since said number r of impulses is smaller than the number n of error impulses and hence corresponds to a lesser correction of the error itself, it will occur that the correction device will be halted before the correction itself has been completed; in this manner any inertia inherent in the mechanical correction device is taken into account and so the correction itself, although it causes the correction device to be halted, will nonetheless be completed, that is it will reach the point at which there is complete annulment of the error.

In the example hereinabove described, said generator of impulses 5 should be assumed to be a single one serving the whole machine, whilst, on the other hand a device for error reading and correction is provided for each roller starting from roller C₂, that is, a device comprising the reading heads, the counter, the sign detector, the correction devices 11 and 12 and the control device 13, is repeated for each of said rollers.

In the second embodiment of the device according to the invention, illustrated in FIG. 3, there are again as in the previous case, two reading heads 6' and 7'; a sign detector 9'; an advancement correction device 11'; a retardation correction device 12' and a control device 13'; similarly also, a counter 10' with related starting circuit 8' is provided.

The members indicated by dashed numerals have similar functions to those of the previous example which are indicated by undashed numerals.

As variants to the device of the previous example a constant frequency impulse generator 18 is provided, that is one whose impulses are independent of the speed of shaft 4 of the machine such as a conventional multivibrator; there are also provided as variants from the previous device, a third reading head 16, a second counter 19 similar to counter 10' with related starting circuit 17 similar to starting circuit 8', and a device 20 which is designed to find the ratio between the numbers of impulses counted respectively by counters 10' and 19, as will more clearly appear hereinafter. As in the previous example, the two heads 6' and 7' read respectively the reference mark and the control mark: the first reading head (6' or 7') sets off circuit 8' thus starting off the counting by counter 10'; the second reading cuts off the counting. The number of impulses counted in the interval between the two readings depends not only on the error ϵ but also, in this case, on the speed of advancement of the paper band 2, that is on the speed of shaft 4, and, to be precise, it is inversely proportional to said speed: in the present example in fact, the impulse gen-

erator 18 is independent of said shaft and the frequency of the impulses is constant.

The third reading head 16 is situated after reading head 6' at a fixed distance therefrom, indicated by the arrow 1 in FIG. 4; the symbols s_1 and s_2 indicate respectively, for illustrative purposes, the reference mark and the control mark, both of which are on the band of paper 2, after printing by the two rollers; arrow F_1 indicates the direction of advancement of the band itself.

The two marks s_1 and s_2 are separated, in the direction of the length of the band, by a distance ϵ which represents the printing error.

It follows from what has already been said in connection with the relative position of heads 6' and 16, that said head 16 also reads the reference mark s_1 after this mark, having already been read by head 6', has traversed the space 1. Besides the functions which have already been described, said head 6', as in the previous example, also has the function of controlling the starting circuit 17 of counter 19 by means of an impulse emitted when reference mark s_1 passes under said head; thereafter, head 16, when reading mark s_1 , passing below it, emits an impulse for the purpose of stopping said starting circuit 17. In this manner counter 19 counts the number of impulses emitted by generator 18 in the interval between the two impulses emitted by heads 6' and 16' respectively. The number of impulses counted by counter 19 is also inversely proportional to the speed of shaft 4, that is to the speed v of advancement of the paper band 2.

There are thus two counters 10' and 19 which count the two numbers n and n' of impulses emitted respectively in the interval between the two impulses emitted by heads 6' and 7', and in the interval between the two impulses emitted by heads 6' and 16'.

Now each of said numbers, considered as variable, is directly proportional to the amount of advancement of the band in the interval under consideration, and inversely proportional to the speed v of this advancement, or to be more precise, the two numbers n and n' are given by expressions of the type:

$$n = K \frac{\epsilon}{v}; \quad n' = K \frac{1}{v}$$

where K is a constant. Consequently the ratio n/n' is given by $n/n' = 1$, that is, whilst the two number of impulses n and n' depend on the speed and consequently on the respective time intervals during which the impulses are counted by counters 10' and 19, said ratio between the two numbers of impulses does not depend on the speed, nor therefore on the time, but simply on the error (1 being a constant).

The device 20 which is connected to counters 10' and 19 works out said ratio and is used to control the correction circuits 11' and 12' as in the previous example; in particular, this device will act as a counter and behave in relation to the correction system in the same manner as counter 10 behaved in the previous example.

Rollers C_2 to C_5 can be checked by first comparing roller C_2 with roller C_1 , then roller C_3 with roller C_2 , and so on; each of rollers C_2 to C_5 can also be compared with the first roller, i.e. roller C_1 .

In this second example also, illustrated in FIG. 3, there is a single impulse generator 18, whilst a device is provided with members for reading and correcting the error at each roller, starting from roller C_2 .

We claim:

1. A control device for controlling the positional relationship when superimposing two monochromatic images printed one after the other on a paper band comprising means for moving said paper band past printing members, at least two reading heads, one reading head for reading a reference mark passing thereunder and the other reading head for reading a control mark passing thereunder and which is to be made coincident with said reference mark, a gate circuit operatively con-

nected to and for receiving impulses from each reading head, main pulse generator means for generating pulses at a predetermined frequency, correction means operatively connected to said moving means, a second pulse generator means operatively connected to said correction means for generating pulses in correspondence to the operation thereof, pulse counter means operatively connected to said gate circuit and pulse generators, said gate circuit controlling said pulse counter means for counting

10 the pulses coming from said pulse generators only when there is a difference between the reference and control marks read by the reading heads, a sensing means, operatively connected between said reading heads and said correction means to select the proper correction to be applied to said moving means in accordance with the reference and control marks being read by said reading heads, and means connecting said pulse counter means to said correction means to stop operation thereof when the pulses from said second pulse generator means to 20 said pulse counter means have reached the corrected valve.

2. A control device according to claim 1 in which said main pulse generator means is operatively connected to said moving means.

3. A control device for controlling the positional relationship when superimposing two monochromatic images printed one after the other on a paper band comprising means for moving said paper band past printing means, at least three reading heads, a first reading head

30 for reading a reference mark passing thereunder, a second reading head for reading a control mark passing thereunder and a third reading head spaced from said first reading head and for reading said reference mark passing thereunder, said reference mark to be made coincident with said control mark, a first gate circuit operatively connected to and for receiving impulses from said first and second reading heads, a second gate circuit operatively connected to and for receiving impulses from said first and third reading heads, a first pulse generator

40 means for generating pulses at a predetermined frequency, correction means operatively connected to said moving means, a second pulse generator means operatively connected to said correction means for generating pulses in correspondence to the operation thereof, first pulse counter means operatively connected to said first gate circuit and first pulse generator means, said first gate circuit controlling said first pulse counter means for counting the pulses coming from said first pulse generator means only when there is a difference between the reference and control marks read by said first and second reading heads, a second pulse counter means operatively connected to and for receiving pulses from said first pulse generator means and second gate circuit, said second gate circuit controlling said second pulse

45 counter means for counting the pulses from said first pulse generator means, a third pulse counter means operatively connected to and for receiving pulses from said first and second counter means and said second pulse generator means, a sensing means operatively connected between said first and second reading heads and said correction means to select the proper correction to be applied to said moving means in accordance with the reference and control marks being read by said first and second reading heads, and means connecting said third

50 pulse counter means to said correction means to stop operation thereof when the pulses from said second pulse generator means to said third pulse counter means have reached the corrected valve.

4. A control device for controlling the positional relationship when superimposing two images printed one after the other on a printing medium comprising means for moving said printing medium past printing means, at least two reading heads for reading reference and control marks respectively, gate means for receiving impulses 70 read by said reading heads, selecting means for receiv-

ing and selecting the impulses read by said reading heads, correcting means for receiving impulses from said selecting means and for operatively controlling same, means connecting said correcting means to said moving means to apply a correction thereto, counter means for receiving impulses from said gate means to control same only when there is a difference between the reference and control marks, generator means for generating impulses of predetermined frequencies into said counter means, and

5

means connecting said counter means to said correcting means to stop same when the pulses from said generator means have reached the corrected valve represented by coincidence between the reference and control marks.
